US00D822703S

(12) **United States Design Patent** (10) **Patent No.:** **US D822,703 S**
Binder et al. (45) **Date of Patent:** ** *Jul. 10, 2018

(54) **DISPLAY SCREEN OR PORTION THEREOF WITH A GRAPHICAL USER INTERFACE**

(71) Applicant: **Layer3 TV, Inc.**, Denver, CO (US)

(72) Inventors: **Jeffrey Binder**, Denver, CO (US); **Miles Fenn**, Denver, CO (US); **Jeff Bacon**, Shrewsbury, MA (US); **Vic Odryna**, Boston, MA (US); **Barry Lam**, Boston, MA (US); **Martin Fisher**, Cambridge, MA (US); **Phil Sutherland**, Wellesley, MA (US); **Patrick Herlihy**, Boston, MA (US)

(73) Assignee: **LAYER3 TV, INC.**, Denver, CO (US)

(*) Notice: This patent is subject to a terminal disclaimer.

(**) Term: **15 Years**

(21) Appl. No.: **29/599,079**

(22) Filed: **Mar. 30, 2017**

(57) **CLAIM**

The ornamental design for a display screen or portion thereof with a graphical user interface, as shown and described.

DESCRIPTION

FIG. 1 is a front view of a display screen or portion thereof with a graphical user interface, shown in the environment of a tablet;

FIG. 2 is a perspective view thereof;

FIG. 3 is a front view of a display screen or portion thereof with a graphical user interface, shown in the environment of a monitor; and,

FIG. 4 is perspective view thereof.

The broken line showing of a display screen with graphical user interface is included for the purpose of illustrating portions of the article and forms no part of the claimed design. The broken line showing of a tablet and monitor is included for the purpose of illustrating environmental structure and forms no part of the claimed design.

1 Claim, 4 Drawing Sheets
